4 Claims. (Cl. 222—183)

The present invention concerns a novel dispensing container which may be stored and sold as a package.

It is an object of the invention to provide a novel paint container in which the paint can be thoroughly mixed so that all pigment is fully dispersed without shaking or the use of special machinery for the purpose.

It is an object of the invention to provide a paint container which is self closing and substantially non-spillable.

It is an object of the invention to provide a paint container which can be used as a receptacle from which paint is applied by a brush or the like in normal course and which can spill only a small portion of its total content volume if inadvertently overturned during paint application and the performance of related work.

It is an object of the invention to provide a paint container which is substantially continuously sealed from the atmosphere even while paint is being dispensed, so that only a relatively small amount of paint necessary for immediate application is exposed to the oxygen of the atmosphere whereby waste is substantially eliminated and the objectionable formation of a tough layer or "skin" of partially hardened paint due to exposure is avoided.

It is an object of the invention to provide a paint container having a concave paint receiving depression in one wall thereof with a self-sealing dispensing spout so positioned with respect to said bowl-like depression that paint can be readily forced from the container through the spout and into the bowl-like depression without spilling and the dispensing spout seals itself as soon as the dispensing force on the paint is removed.

The invention may take the form of an open ended cardboard cylinder which is substantially filled with a plastic sack or bag containing a quart or half-gallon of mixed paint ready for sale. The upper, normally open end of the plastic sack is folded over the upper edge of the cylinder and held in firmly sealed position by the crimped flanged edge of a dished metal closure forming a bowl-like depression from which a self-sealing dispensing spout projects. The bottom open end of the outer cylinder is preferably crimped in a metal rim of U-shaped cross-section to give strength to the package. The self-sealing dispensing spout is provided with a positive seal cap which fits snugly over the spout and may be threaded thereon, if desired. With the positive seal cap in place, the plastic bag can easily be kneaded in the hand to mix the paint thoroughly and make it ready for use. After the cap is removed, the bag may be squeezed to force paint out through a diagonal slit in the flexible material of the spout and into the bowl-shaped depression. As soon as the bag is released, the flow of paint stops and the slit in the spout closes of itself as the spout material returns to its normal cylindrical shape. A brush is then dipped into the paint in the depressed top member and applied to a desired surface. Only the small amount of paint remaining in the depression is exposed to the air or can be spilled by an accidental, or for that matter intentional, overturning of the entire can.

Reference is made to the drawings wherein like numerals refer to like parts throughout. The several figures are intended to be illustrative only and are not to be taken as limiting.

2

In the drawings:

FIGURE 1 is a perspective view of one form the invention may take with a part of the outer wall cut away to show the plastic bag in position.

5 FIGURE 2 is an elevation of the container of FIGURE 1, partially sectioned down the middle.

FIGURE 3 is a fragmentary section of a modified form of the invention.

10 FIGURE 4 is an enlarged section of one form of crimp sealing of the container package.

FIGURE 5 is an enlarged section of one form of self-sealing dispensing spout of the invention.

A cardboard cylinder 10 of suitable wall thickness to give adequate strength is preferably provided with a bottom strengthening 11 which may be stiff plastic or metal formed into a U cross-section into which the bottom of cylinder 10 fits snugly and is firmly crimped in place as clearly shown in FIGURE 4. Inner wall 12 of U-shaped ring 11 extends high enough to afford a firm grip on cylinder 10. The outer wall of U-shaped ring 11 is preferably higher than inner wall 12 to afford full protection for outer wall 10 and prevent it from deforming under stress.

A plastic bag 13 containing liquid material 14 is positioned in depending relation inside cylinder 10 with its edge portion 15 folded over the top and down the side of cylinder 10. A top member 16 of metal or stiff plastic material is formed into a segment of a sphere, to form a bowl-like depression 17 with down-turned flange 18. Flange 18 extends around the upper edge of cylinder 10, down the side over edge portion 15 of plastic bag 13 and is crimped to hold top member 16 firmly in place on the upper end of cylinder 10 with the material of plastic bag 13 and edge portion 15 securely therebetween in a liquid tight seal. The enlarged showing of this seal in FIGURE 4 is merely illustrative. The patented art is replete with similar seals having additional folds and bends and adhesive liquid-proof sealing compounds for assuring that this joint will withstand the forces and strains to which it will be subjected without leaking liquid or admitting ambient air into the interior of bag 13 where it could oxidize or contaminate the contents 14.

An inlet-outlet tube 19 is shown integral with depression 17 of top closure member 16. This tube or spout 19 may be a separate element having an open flange securely fastened to the concave or convex surface of depression 17 and in either case communicates freely with the interior of bag 13. Spout 19 is provided with a slit 20 which is curved upwardly or downwardly around the cylindrical wall of spout 19. The material of spout 19 has sufficient resilience and restoring strength to maintain slit 20 closed and substantially liquid proof until subjected to an internal force applied to the liquid contents 14 which causes the closed top 23 of spout 19 to lift and rotate slightly on a spring-like hinge formed by the unslotted portion of the cylindrical wall of spout 19 separating the ends of the diagonal slit 20. The force applied by hand to the liquid 14 forces slit 20 open and the cylindrical shape of the unslit portion of the tube 19 is slightly distorted thereby. As the material is resilient and has spring action a restoring force is engendered which causes the tube 19 to resume its original cylindrical shape and to close diagonal slit 20 as it does so. The material of tube 19 has sufficient stiffness that the mere static weight of a pint, quart, or half-gallon of paint or other liquid 14, as the case may be, cannot alone force the slit 20 open if the entire container is turned on its side or upside down. It should be able to withstand a drop of at least several feet onto a hard floor. A separate permanent closure cap 22 fits snugly over the closed end 23 and slit 20 of tube 19 when not in use to assure against inadvertent leakage from any cause short of

rupture of bag 13. Cap 22 may be threaded into place if desired.

Just as the tube 19 may be a separate element not integral with surface 17 but firmly attached thereto by an open flanging so also may the upper section of tube 19 containing slit 20 and closed end 23 be a separate section of larger diameter which may be slipped over the open stub of tube 19 sealed firmly into place after the bag 13 is filled with paint. Slit 20 may also be opened by bending the tip 23 by hand or machine for filling or dispensing.

The tube 19 may be displaced from center as at 19 in FIGURE 3 to permit squeezing the remnants of contents out of bag 13 and to allow the easy use of a larger brush or paint roller, especially in the smaller pint sizes.

The container 13 is preferably filled through tube 19 though the plastic bag 13 or surface 17 may be readily punctured and resealed for such purpose. In the preferred form, the bag 13 is first collapsed by withdrawing as much air as practicable before filling, which may be complete, leaving no voids. The flexible character of bag 13 allows for expansion and one feature of the invention is the elimination of an oxidizing atmosphere within the can at all times. If gas space is deemed necessary, nitrogen or carbon dioxide can be introduced or only a small amount of air permitted to remain.

The device lends itself to other uses such as a supply of liquid food for birds and animals. Multiple feedings are practicable from the same container while travelling or when medication is desired. Depression 17 provides a feeding bowl and may be marked by suitable lines to indicate a measured quantity which may be accurately dispensed.

For the storage of the dispensing package on shelves and in warehouses it is desirable to provide a nesting construction so as to lend stability to stacks of the dispensing containers. To this end the bottom rim 11 may be inset slightly to nest in the upper portion 16. This is preferably accomplished by an internal flanging which is turned inwardly and downwardly to give a firm nesting relation with the upper edge 16 of the dispensing package next below in the stack.

While there have been described above what are presently believed to be the preferred forms of the invention variations thereof will be obvious to those skilled in the art and all such changes and variations which fall within the spirit of the invention are intended to be covered by the generic terms in the appended claims, which are variably worded to that end.

I claim:

1. A dispensing package for liquids, said package having a relatively stiff outer wall member of sufficient strength and a base broad enough to support the package in an upright stable position, a collapsible closed inner member supported by said outer member, outlet means for said inner member, said outer member having means to facilitate the application of force to the flexible closed inner member to dispense contents of the package, a recessed upper closure for said outer member, said inner member

comprising a plastic bag the edges of which are clamped between the upper edge of said outer wall member and said closure in liquid sealing relation, said recess forming an open reservoir for a limited amount of liquid to be dispensed by the package, said reservoir being concave and covering the major part of said closure, said outlet means comprising a slotted tube projecting into the concave side of said upper closure and positioned to dispense liquid into said reservoir, said reservoir being readily accessible for the repeated application of said liquid in use.

5 2. A dispensing package for liquids comprising a substantially cylindrical outer member of sufficient structural strength to support said package with its liquid contents in air and liquid tight conditions, a collapsible inner bag member, dispensing outlet means for said inner bag member, means attaching said inner bag member firmly to said outer member and comprising a flanged closure member gripping one end of said outer member to form a liquid tight seal with the edge of said bag member firmly fastened 15 between said closure member and said outer member, said flanged closure member being recessed to provide an open reservoir for said package for receiving a limited amount of liquid dispensed by the package, said cylindrical outer member having an open bottom to facilitate the deforming 20 of said inner member for mixing and for the dispensing of the contents of said package, said flanged closure member mounting said dispensing outlet means in communication with the interior of said inner bag member for the controlled dispensing of said liquid contents into said reservoir 25 30 whereby a small quantity of liquid dispensed into said reservoir may be used and the supply renewed as needed, said dispensing outlet means being constructed to open into a dispensing condition in response to the application of a deforming force to said inner bag and to close upon the removal of such deforming force whereby an upsetting of 35 said package will spill only the quantity of contents present in said recess, and means for selectively maintaining said dispensing outlet means closed during the deformation of said inner bag for mixing the contents prior to dispensing.

3. The combination set forth in claim 2, said recess in said flanged closure member being a segment of a sphere and said dispensing outlet means comprising a tube having a diagonal slot therein.

4. The combination set forth in claim 3, said outer member having a reinforcing element around its open edge to maintain the shape of the package and to aid in protecting the inner bag member.
